(57) **CLAIM**

I claim the ornamental design for a pill card, as shown and described.

DESCRIPTION

FIG. 1 is a front elevation view of my design for a pill card.

FIG. 2 is a back elevation view thereof.

FIG. 3 is a top plan view thereof.

FIG. 4 is a bottom plan view thereof.

FIG. 5 is a left side elevation view thereof; and,

FIG. 6 is a right side elevation view thereof.

The broken lines and the sections within the broken lines represent portions of the pill card that form no part of the claimed design.

1 Claim, 2 Drawing Sheets
